UNITED STATES PATENT OFFICE

2,690,031

ANIMATED FIGURE TOY

Romualdo Camuso, Irvington, N. J., assignor to
 The Lionel Corporation, New York, N. Y., a
 corporation of New York

Application June 13, 1952, Serial No. 293,323

1 Claim. (Cl. 46—12)

1

This invention relates to animated figure toys and is more particularly directed toward animated figure toys adapted to simulate the operation of a watchman in moving from one position to another and in the second position simulating the swinging of a signal lantern.

The present invention is particularly suited for employment in toy railroad accessories of the type which have a house or watchman's shanty with mechanism for moving the watchman in and out of the shanty through an open doorway, and according to the present invention devices are provided which effect a sudden swinging of the watchman's arm from hanging position to elevated position at the end of the outward stroke of the watchman's shifting mechanism.

The present invention is shown here as employed in the type of animated figure toy shown more fully in Bonanno application, Serial No. 239,681, filed August 1, 1951.

The accompanying drawings show, for purposes of illustrating the present invention, one embodiment in which the invention may take form, it being understood that the drawings are illustrative of the invention rather than limiting the same.

In the accompanying drawings:

Figure 1 is a perspective view of the animated figure toy showing the toy house with the door open;

Figure 2 is a horizontal section through the toy house with the door closed;

Figure 3 is a front view of the toy house with the watchman in retracted position, in section on the line 3—3 of Fig. 2;

Figure 4 is a vertical sectional view on the arc 4—4 of Figure 2 and the plane 4—4 of Figure 5;

Figure 5 is an elevational view of the watchman taken in the direction of the arrow 5 of Figure 4.

As shown in the perspective view of Fig. 1, the animated figure toy has a base 10, a house 11 with the door 12 in the doorway or door opening, and a toy figure or manikin simulating the gateman or signal man. The device simulates the gateman's shanty alongside the usual railroad track.

As shown in the drawings, the base 10 is, for convenience, a rectangular shaped sheet metal member with downwardly extending flanges 15. It supports the toy house 11. The door 12 for the toy house has an upwardly extending pintle 16 entering into the recess in the top of the door-

2

way of the toy house and has a pivot post 17 which passes down through an opening in the base 10. The lower end of the pintle 17 carries a molded plastic gear member 18 with a lower flange 19 preferably somewhat larger in diameter than the outer diameter of the gear.

The base 10 carries a pivot post 20 some distance beyond the other edge of the doorway. This pivot post carries a sector shaped arm 21 having teeth 22 which mesh with the teeth of the gear 18. The lever arm 21 is similarly held in place on pin 20 and also against separation from the gear 18 by the flange 19. The sector arm 21 carries a post 26 which extends up through an arcuate slot 27 in the base and carries a manikin or figure 13 above referred to.

The arm 21 is biased to the position shown in full lines in Figure 2 by a spring 28. When the parts are in this position, the figure or manikin is inside the toy house and the door of the toy house is closed. The base 10 also carries a solenoid coil 30 having a magnetizable plunger 31 whose free end 32 bears against the edge 33 of the lever arm 21. The mechanism carried in the base 10 is covered and protected by a bottom cover member 37.

The right arm 40 of the manikin is hinged at the shoulder and operably connected to a wire rod or lifter 41 which extends down through a guide hole 42 near the manikin's feet. The lower end 43 of the lifter is bent as indicated at 44. It is brought against a cam 45 bent out of the material of the base 10 and rides up this cam during the forward stroke of the mechanism and swings the arm from the lower full line position of Figure 4 to the upper or dotted line position of this figure, so that the lantern 46 is displayed more effectively. It swings violently when the mechanism comes out of the shanty.

Since it is obvious that the invention may be embodied in other forms and constructions within the scope of the claim, I wish it to be understood that the particular form shown is but one of these forms, and various modifications and changes being possible, I do not otherwise limit myself in any way with respect thereto.

What is claimed is:

A toy comprising a toy house having a doorway, a base supporting the toy house, a door pivotally supported by the base and the top of the doorway near one edge thereof for swinging outwardly, a gear carried by the lower door pivot below the base, a toothed sector meshing with the gear and pivoted to the base beyond the other

edge of the doorway, a spring acting on the sector to hold the door closed, a post extending upwardly from the sector and passing through a slot in the base partly behind the doorway and partly in front of it, a manikin carried on the post and movable through the doorway when the sector moves the door open and retreating into the building when the door closes, the manikin having a swingable arm, a lantern carried by the arm, an operator for the sector to move it against the spring to open the door and advance the figure, a fixed cam element past which the manikin moves near the forward end of its move- 5 10

ment, and a follower engageable with the cam and connected to the arm on the manikin to lift the arm and swing the lantern.
